DRAINPIPE VALVE

Zygmund Bugno, Chicago, Ill.

Application December 27, 1948, Serial No. 67,460

5 Claims. (Cl. 137—104)

1

In connection with drain pipes connecting with a basement floor and a catch basin, it frequently occurs that the basement floor becomes flooded due to the rise of water in the catch basin. Accordingly, the principal object of the present invention is the provision of a suitable valve co-acting with the end of a drain pipe which remains in the catch basin for automatically shutting off that end and thereby preventing the backing up of water from the catch basin into the basement.

Another object of the present invention is the provision of a suitable mechanism operable by a float for actuating the valve into an operative or inoperative position with relation to the drain pipe for closing or opening the latter.

A still further object of the present invention is the provision of a valve cooperating with the end of the drain pipe, disposed within a catch basin, operable by a float for shutting off the drain pipe as the water in the catch basin rises for preventing the water to pass into the basement through the drain pipe.

A still further object of the present invention is the provision of suitable tensioning means in connection with a valve of the character indicated, which facilitate the valve to come into operative or inoperative positions, when actuated by a float, for shutting off or opening the drain pipe.

Another object of the present invention is to generally improve a valve of the character hereinabove indicated.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application and in which like designating characters refer to corresponding parts throughout the several views;

Fig. 1 is a vertical cross-section through a catch basin with the end of a drain pipe in an operative position therewith, with the valve in an operative position with the drain pipe, the drain pipe and the valve being shown in elevation;

Fig. 2 is an enlarged, side elevational view of the drain pipe with the valve in an operative position therewith;

Fig. 3 is a similar view taken substantially at ninety degrees from the position thereof shown in Fig. 2; and

Fig. 4 is a cross-sectional view taken on line 4—4 of Fig. 2.

Referring in detail to the present drawing there is shown therein catch basin 10, provided

2

at its upper end with conventional closure 11. Let into said catch basin 10 is one end of drain pipe 12, which partially extends into said catch basin 10. The other end of said drain pipe 12 leads to the basement of a dwelling and usually is directed vertically for providing drainage from the basement into the catch basin.

To adapt said drain pipe 12 for operation with the valve constituting the subject matter of the present invention, the end of said drain pipe remaining within catch basin 10 is shut by closure 13, provided with handle 14, by means of which said closure 13 may be either inserted into or withdrawn from the end of said drain pipe 12. Further, U-shaped pipe 15 is connected by one of its ends with said drain pipe 12, preferably at a lowermost point of the periphery of the latter. Said U-shaped pipe 15 constitutes a seal, when filled with water, for preventing passage of gases from the catch basin into the basement.

The other end of said U-shaped pipe 15 is provided with outwardly flaring mouth 16, and therebelow is provided with encompassing ring 17 which is rigidly affixed to said U-shaped pipe 15. Either rigidly affixed to said ring 17 or integrally formed therewith are four arms 18 radially projecting from said ring 17. One of said arms 18, which extends into a lateral direction with relation to said U-shaped pipe 15 is longer than the remaining three of said arms 18, as seen in Fig. 3, for the purpose hereinafter specified.

Each of said arms 18 is formed in the shape of an angle bar, to include horizontal portions 19. Extended through horizontal portion 19 of each arm 18 is rod 20, each of which is rigidly maintained by a pair of nuts 21 threadedly engaging each rod 20 and holding horizontal portion 19 of each arm 18 in a clamped interposed relation. Said rods 20 are directed upwardly.

Affixed to the outer end of the longest of said arms 18 is supporting standard 22 extended therefrom to a vertical direction. Pivoted upon pin 23, passing through said supporting standard 22, is bar 24, which is capable to make angular swinging motions upon said pin 23. Suspended upon one end of said bar 24 is float 25.

Said bar 24 is also made in the shape of an angle bar and through the horizontal portion of which, at the opposite end, rod 26 is extended. Rigidly affixed to the lower end of said rod 26 is valve head 27 which is disposed over mouth 16 of said U-shaped pipe 15, in a vertical relation.

Disposed above said valve head 27 is spider plate 28, through the center of which said rod 26 is passed and to which said spider plate 28 is clamped by means of nut 29. Said spider plate 28 effects four prongs 30, each of which is in a vertical alignment with each arm 18. Through

each of said prongs 30 one of said rods 20 is passed.

Threadedly engaging the upper end of each rod 20 is nut 31. Interposed between nut 31 and a given prong 30, and in an encompassing relation with each rod 20 is coil spring 32.

Coil spring 33 is interposed between nut 29 and the horizontal portion of bar 24 and is in an encompassing relation with said rod 26.

Set upon the upper end of rod 26 is coil spring 34, which is interposed between the horizontal portion of bar 24 and nut 35, the latter being in a threaded engagement with the upper termination of said rod 26.

In the inoperative, open position of valve head 27 with relation to mouth 16 of U-shaped pipe 15, bar 24 remains in a horizontal position. In that inoperative position of valve head 27, springs 32, bearing against prongs 30, and spring 34, bearing against the horizontal portion of bar 24, prevent the adjacent end of said bar 24 to make any further upward shifting movement, and counteract the weight of float 25. When however water in catch basin 10 rises it elevates float 25, causing the adjacent end of bar 24 to shift upwardly, thereby causing the opposite end of said bar 24 to shift downwardly. The downward shifting of said latter end of bar 24 exerts pressure upon coil spring 33 and causes the latter to press upon nut 29 for shifting plate 28 and valve head 27 downwardly. This action brings valve head 27 into mouth 16, effectively closing the latter and preventing the collecting water in catch basin 10 from passing into U-shaped pipe 15 and drain pipe 12.

The unusual amount of water in catch basin 10, which may rise above float 25 and bar 24 and submerge the two, will not detract from the operativeness of the valve. Water submerging float 25 will increase its buoyancy and thereby the pressure of bar 24 at its end adjacent rod 26, thereby further compressing spring 33, and when the latter is compressed to the fullest extent, the end of said bar 24 above spring 33 will be incapable of further downward shifting. When valve head 27 remains in an operative position within U-shaped pipe 15, springs 32 and 34 remain entirely in a loose condition upon their respective rods 20 and 26.

When water in the catch basin falls float 25 will necessarily fall with it for shifting bar 24 back into its normal, inoperative, horizontal position. The shifting of said bar 24 into that latter position is assisted by spring 33 as it bears pressure upon the underface of the horizontal portion of said bar 24 for driving the adjacent end of said bar 24 upwardly. This action of course elevates plate 28 with its prongs 30 and brings valve head 27 out of mouth 16 of U-shaped pipe 15. In the inoperative position of valve head 27 springs 32, bearing against prongs 30, and spring 34, bearing against the horizontal portion of bar 24, provide means for maintaining said bar 24 in a horizontal position by counteracting the weight of float 25, which at this stage is not supported by water but hangs upon the adjacent end of said bar 24. In any sudden fall of water in catch basin 10 said springs 32 and 34 act as cushions for preventing jarring of the mechanism as the adjacent end of bar 24 makes sudden upward thrust.

Rods 20, being passed through prongs 30, constitute guiding means for said spider plate 28 and valve head 27, by virtue of which arrangement valve head 27 is guided in its shifting in a

true vertical direction so that it may be shifted into mouth 16 or out of it without difficulty and without disarrangement of parts. The opening in the horizontal portion of bar 24, through which rod 26 is passed, should be made oblong relative to the length of said bar 24, so as to permit accommodation of said bar 24 with relation to said rod 26 as the former makes angular shifting motions with relation to said rod 26.

While there is described herein a preferred embodiment of the present invention, it is nevertheless to be understood that minor changes may be made therein without departing from the spirit and scope of the invention as claimed.

What I claim as new is:

1. A float valve operable by rise and fall of water for closing or opening the mouth of a pipe comprising a supporting member mounted upon the pipe, a plate overlying the mouth of the pipe, 20 a valve head carried by said plate, a plurality of rods carried by said supporting member, said rods extending through said plate for guiding the latter toward or away from the mouth of the pipe, a standard carried by said supporting member, 25 a bar pivoted to said standard, a float carried by one end of said bar, a rod affixed to said plate and said valve head, said rod being passed through the opposite end of said bar, and a coil spring upon said rod interposed between said plate and said opposite end of said bar, when said float rises due to the rise of water said bar being adapted for angular shifting movement for bearing upon said coil spring for shifting said plate and said valve head for driving said valve head into the mouth of the pipe.

2. A float valve operable by rise and fall of water for closing or opening the mouth of a pipe comprising a supporting member including a plurality of arms radially extending from the pipe, a plate overlying the mouth of the pipe, a plurality of prongs extending from said plate, said prongs being in alinement with said arms, a valve head carried by said plate, a rod carried by each of said arms, each rod extending through each prong for guiding said plate toward or away from the mouth of the pipe, a standard carried by one of said arms, a bar pivoted to said standard, a float carried by one end of said bar, a rod affixed to said plate and said valve head, said last named rod being passed through the opposite end of said bar, and a coil spring upon said rod interposed between said plate and said opposite end of said bar, when said float rises due to the rise of water said bar angularly shifting for bearing against said coil spring for shifting said plate and said valve head for driving said valve head into the mouth of the pipe.

3. A float valve operable by rise and fall of water for closing or opening the mouth of a pipe comprising a supporting member including a plurality of arms radially extending from the pipe, a plate overlying the mouth of the pipe, a plurality of prongs extending from said plate, said prongs being in alinement with said arms, 60 a valve head carried by said plate, a rod carried by each of said arms, each rod extending through each prong for guiding said plate toward or away from the mouth of the pipe, a standard carried by one of said arms, a bar pivoted to said standard, 65 a float carried by one end of said bar, a rod affixed to said plate and said valve head, said last named rod being passed through the opposite end of said bar, a coil spring upon said rod interposed between said plate and said opposite end of said bar, when said float rises due to the

rise of water said bar angularly shifting for bearing against said coil spring for shifting said plate and said valve head for driving said valve head into the mouth of the pipe, and another coil spring set upon said last named rod at the opposite side of said bar for limiting the movement of the latter into its inoperative position when said float falls due to the fall of water.

4. A float valve operable by rise and fall of water for closing or opening the mouth of a pipe comprising a supporting member mounted upon the pipe, a plate overlying the mouth of the pipe, a valve head carried by said plate, a standard carried by said supporting member, a bar pivoted upon said standard, a float carried by one end of said bar, a rod affixed to said plate and said valve head, said rod being passed through the opposite end of said bar, connecting means between said opposite end of said bar and said head valve, said bar being adapted for angular shifting movement when actuated by the rising float due to the rise of water, through said connecting means said valve head shifting into the mouth of the pipe when said bar angularly shifts, and means upon said rod for maintaining said bar in a substantially horizontal inoperative position when said float falls due to the fall of water.

5. A float valve operable by rise and fall of water for closing or opening the mouth of a pipe comprising a supporting member mounted upon the pipe, a plate overlying the mouth of the pipe, a valve head carried by said plate, a standard

carried by said supporting member, a bar pivoted upon said standard, a float carried by one end of said bar, a rod affixed to said plate and said valve head, said rod being passed through the opposite end of said bar, a coil spring interposed between said plate and said opposite end of said bar, and a coil spring set upon the free end of said rod coacting with the opposite face of said bar, when said float rises due to the rise of water said bar being adapted for angular shifting movement for bearing upon said first named coil spring for shifting said plate and said valve head for driving said valve head into the mouth of the pipe, the other of said coil springs acting as a cushion against said bar when the latter shifts into the opposite direction for maintaining said bar in its inoperative substantially horizontal position.
